GAS HOLDER

Filed Aug. 29, 1928

UNITED STATES PATENT OFFICE

JOHN R. L. SANTOS, OF BALTIMORE, MARYLAND, ASSIGNOR TO THE BARTLETT HAYWARD COMPANY, OF BALTIMORE, MARYLAND, A CORPORATION OF MARYLAND

GAS HOLDER

Application filed August 29, 1928. Serial No. 302,783.

This invention relates to waterless gas holders, and particularly to means for sealing the joint between the vertically movable piston and the shell of the holder.

5 The purpose of the invention is to provide a peculiarly flexible packing structure, which while maintaining a tight seal, will impose minimum friction upon the upward and downward movement of the piston.

10 A practical embodiment of the invention is illustrated in the accompanying drawing, in which,—

15 Fig. 1 is a fragmentary plan view of a portion of the shell of the holder and of the peripheral portion of the coacting piston.

Fig. 2 is a section on the line 2—2 of Fig. 1, drawn on a slightly enlarged scale.

20 Fig. 3 is a fragmentary view looking at the rear face of the movable packing element.

Fig. 4 is a perspective view looking at the front or sealing face of the packing element.

25 In the drawing a cylindrical holder shell is illustrated, but it will be understood that the invention can be applied, with minor and obvious modifications, to holders of polygonal cross section.

30 The vertical wall or shell of the holder is indicated at 6. The piston includes a plate-like structure 7, a depending skirt or flange 8, and a peripheral trough surrounding the lower portion of the skirt 8 and made up of a bottom plate 9 and an encircling plate 11. The piston structure as a whole may be guided

35 in any familiar way, for example, by means of rollers 12 which engage the shell 6 and which are supported on brackets 13, only one roller and bracket being shown.

40 The trough structure just mentioned is slightly smaller than the internal diameter of the shell 6 and is used to retain a bath 14 of lubricant.

45 Encircling and spaced from the skirt 8 is an annular flexible member 15 which may be made up of any suitable material, but preferably is made of flexible sheet material having the general physical characteristics of fabric belting. It should be quite flexible and impervious to the gas confined in the holder and to the liquid lubricant making up

the bath 14. This annulus 15 is backed by a series of spaced blocks 16 to which are bolted brackets 17.

55 Mounted on the top plate 7 of the piston are a plurality of brackets 18, to which are pivoted, at 19, the levers 21. The levers 21 are also pivoted to corresponding brackets 17, as shown at 22, and carry weights 23 so arranged as to urge the lower ends of the levers 21 outward, thus tending to distend 60 the annulus 15 and force it toward the wall 6 of the shell. In other words the weighted levers form yielding means to distend the annulus. The lower margin of the annulus 15 dips into the lubricant bath 14 and forms a 65 dip seal therewith. The upper end carries a sealing structure made up of a plurality of strips 25 of absorbent material, for example, felt. It is impracticable to make these strips continuous around the piston and they are therefore made in sections, but the joints between adjacent sections are staggered so as to preclude leakage.

70 The strips 25 are confined between an upper angle iron 26 and a lower angle iron 27, both of which are riveted through the annulus 15 to the blocks 16. The rivets are clearly indicated at 28. The strips are further confined by a series of vertical bolts 29 which pass through the horizontal flange of 80 the angles 26 and 27 and through the intervening strips 25.

75 It will be observed that the surface of the lubricant bath 14, on the outer side of the annulus 15, is subject to the pressure of the gas 85 confined in the shell 6 below the piston. It follows therefore that this gas pressure is sufficient to support a considerable column of liquid which rises between the annulus 15 and the skirt 8. The parts are so designed 90 that the upper liquid level is below but near the top of the annulus 15. This provides a convenient means for feeding lubricant to the packing strips 25.

95 To accomplish this result oil feeding apertures 31 are formed in the annulus 15 which are so positioned as to register the gaps or intervals 32 formed between sections of one of the strips 25. In the example illustrated the second strip from the top is interrupted 100

to afford these intervals, but any desired arrangement might be made so long as lubricant will be fed to the surface of contact between the group of strips 25 and the shell 6. As just noted, oil is referred to as the lubricant, and such oil may be light or heavy, or a light tar may be employed.

In a prior application Serial No. 302,782 filed August 29, 1928, I have described and claimed a packing structure in which the packing element is sealed in a bath of liquid and the pressure of gas in the holder is used to feed the lubricant. Consequently no broad claim to that construction is made herein.

What is claimed is,—

1. In a waterless gas holder, the combination of a shell; a piston vertically movable therein to vary the effective volume of the holder; a liquid-retaining trough encircling the piston; a packing structure encircling the piston, contacting the shell and forming a freely movable dip seal with the liquid in the trough, the liquid in the trough being subject to the pressure of the gas within the holder, said arrangement providing means for forcing the lubricant to the packing; and a plurality of weighted levers for movably supporting and guiding the packing structure.

2. In a waterless gas holder, the combination of a shell; a piston vertically movable therein to vary the effective volume of the holder; a lubricant-retaining trough carried by the piston and encircling the same, the lubricant therein being subject to the pressure of the gas within the holder; an annular flexible member surrounding the periphery of the piston; a series of supports serving to sustain said annular member with its lower edge pendant in the lubricant in said trough; means tending at all times to urge said annular member toward the shell; and a substantially continuous sealing element carried by said flexible annular member and contacting said shell, said sealing member cooperating with the annular member aforesaid to provide means for forcing the lubricant to the sealing element by action of the pressure of the gas upon the lubricant.

3. In a waterless gas holder, the combination of a shell; a piston vertically movable therein to vary the effective volume of the holder; a lubricant-retaining trough carried by the piston and encircling the same; an annular flexible member surrounding the periphery of the piston; a series of movable supports serving to sustain said annular member with its lower edge pendant in the lubricant in said trough; means tending at all times to urge said annular member toward the shell; a substantially continuous sealing element carried by said flexible annular member and contacting said shell; and means directly operated by the pressure of

the confined gas to feed lubricant from the trough to said sealing element.

4. In a waterless gas holder, the combination of a shell; a piston vertically movable therein to vary the effective volume of the holder; a retaining trough for liquid lubricant carried by and encircling the piston, the liquid in said trough being subject to the pressure of the gas within the holder; an annular flexible member having the general characteristics of fabric belting encircling the piston with its lower edge dipping into the liquid in said trough; a plurality of levers mounted on the piston and supporting said flexible member at short intervals; means for urging said levers toward the shell; and sealing means carried by said flexible member and engaging the shell, said sealing means cooperating with the annular flexible member aforesaid to provide means for forcing the lubricant liquid to the sealing element by action of the pressure of the gas upon the lubricant.

5. In a waterless gas holder, the combination of a shell; a piston vertically movable therein to vary the effective volume of the holder; a liquid-retaining trough carried by and encircling the piston; an annular flexible member having the general characteristics of fabric belting encircling the piston with its lower edge dipping into the liquid in said trough; a plurality of levers mounted on the piston and supporting said flexible member at short intervals; means for urging said levers toward the shell; sealing means carried by said flexible member above the margin of said trough; and means rendered effective by direct pressure of gas within the holder beneath the piston for feeding lubricant from said trough to said sealing means.

6. In a waterless gas holder, the combination of a shell; a piston vertically movable therein to vary the effective volume of the holder; a lubricant-retaining trough; a packing structure encircling the piston, contacting the shell and forming a dip seal with the lubricant in the trough, said lubricant being subject over a portion of its area to the direct pressure of the gas within the holder; and means for feeding lubricant elevated by said pressure to the area of contact between the packing structure and the shell.

In testimony whereof I have signed my name to this specification.

JOHN R. L. SANTOS.
